UNITED STATES PATENT OFFICE.

JOHN C. NICHOLS, OF SHEBOYGAN, WISCONSIN, ASSIGNOR TO JOHN C. NICHOLS HARNESS MFG. COMPANY, OF SHEBOYGAN, WISCONSIN, A CORPORATION OF WISCONSIN.

HORSE-COLLAR CONSTRUCTION.

1,238,556.

Specification of Letters Patent.

Patented Aug. 28, 1917.

Application filed May 16, 1917. Serial No. 169,009.

To all whom it may concern:

Be it known that I, JOHN C. NICHOLS, a citizen of the United States, residing at Sheboygan, in the county of Sheboygan and 5 State of Wisconsin, have invented new and useful Improvements in Horse-Collar Constructions, of which the following is a specification.

This invention relates to horse collars generally, and is more particularly directed to the provision of a covering or facing constructed of separate patterns or elements united to the collar along their contacting ends, enabling the parts constituting the collar, namely, the rim, forewale, crooks, straights, face or liner, throat, and neck band flaps, to be given the desired shape and flexibility, whereby in the manufacture of the collars liability to rupture at the 10 seams is diminished, and the durability, appearance and fitting are increased.

With the above and other objects in view, the invention consists in the novel features, details of construction and combination of 15 parts which will hereinafter be more fully set forth, illustrated in the accompanying drawings and pointed out in the appended claim.

Figure 1 is a perspective view of a horse collar with the facing strips or patterns assembled to the collar;

Fig. 2 is a rear view;

Fig. 3 is a transverse section taken on line 3—3 of Fig. 1; and

Figs. 4 to 14 inclusive are plans of the blanks or patterns.

Referring more particularly to the accompanying drawings, I have shown in Fig. 4 of the drawing the pattern or element constituting the facing strip for the rim or forewale 5 of the collar, denoted by the character 6, and is illustrated as formed of leather or the like flexible material. This rim or forewale facing constitutes a continuous strip of material of substantially equal width throughout its length and formed with slightly tapering upper ends 7. The facing strip or pattern for the face or liner 8 of the collar is indicated by the character 9 and will be hereinafter referred to for the sake of clearness as the face or liner facing strip which is better shown in Fig. 5 of the drawing. This facing strip is provided with a reduced upper end 10, a reduced lower end 11, and the material forming the strip

increases in transverse dimensions at points between the upper and lower ends thereof to provide the upper half of the facing strip for a portion of its length with a straight downwardly and outwardly inclined outer edge, while the remaining length or lower portion of the strip presents a bulged gracefully curved outer edge, indicated by the characters 12 and 13 respectively, the purpose of which will be hereinafter more fully set forth. The inner edge of the face or liner strip is indicated generally by the character 14. It will, of course, be understood that in the construction of the collar a pair of these strips will be employed for covering the opposite faces or liners forming the collar.

In Fig. 6 I have illustrated the pattern or crook facing strip indicated generally by the character 15 and gradually decreasing in transverse dimension throughout its length to provide the same with a straight broad upper edge 16 and a reduced lower end 17, the latter referred to end to an extent overlapping the throat 18 of the collar. It is manifest that one of these strips is employed for each of the crooks of the collar and are united along their straight broad upper edges by a seam, to what is known as a wear strip, indicated generally by the character 19 and better shown in Fig. 7 of the drawing. This pattern or element known as the wear strip gradually increases in transverse dimension throughout its length to provide the same with a concaved inner edge 20, a convexed outer edge 21 and outwardly inclined side edges 22, it being understood that the seam 23 connecting one of the edges 22 with the upper edge 16 of the crook strip may be either formed by machine or hand stitching, while the opposite side edge 22 of the wear strip is united to the broad lower edge 24 of the straight strip of the collar, denoted by the character 25. The straight strip serves as a covering or facing for the straights of the collar and gradually decreases in transverse dimension from the broad bottom edge 24 toward the lower end thereof, presenting the same with a downwardly and outwardly inclined inner edge 26 and a downwardly curved or convexed forward edge 27. The upper portion of the front strip 27 of the straight strip 25 is concaved as at 28, and thence gradually

merges outwardly to provide the upper free end of the front edge bulged outwardly as at 29. The piece illustrated in Fig. 9 of the drawing denotes an inner throat piece 30, while the illustration in Fig. 10 of the drawing designates an outer throat or covering 31, each of which being of substantially keystone shape, and having their outer edges sewn by the closing seam 32 and the shaping seam 33, and when so connected reinforcing the inner and outer faces of the throat and overlapping the end 17 of the crook or facing strips or pieces 15. The closing seam, aside from securing the flexible rim to the side of the respective inner and outer throat pieces, further unites the inner edges of the crook facing strips, the wear facing strips and the straight strip together, whereas the shaping seam unites the inner ends of the respective inner and outer flexible neck band pieces 34 and 35 respectively in overlapped relation and to the upper edge of the straight pieces 25, after which the shaping seam is brought through the herein stated coverings or pieces, and not only renders a uniform shape to the collar, but further provides around the outer edge of the collar as its entirety a flange 36 of a two-fold thickness. The facing strips covering the entire collar construction are completed by securing to the neck bands liners 37. The inner and outer flexible neck band pieces are each provided with a row of openings 38 which, upon the uniting of the neck band pieces together, are arranged in spaced parallel relation one to the other,

and through which prongs of the collar pad 39 project. Riveted or otherwise suitably secured to the under face of the neck pad is a further flexible strip or facing 40 known as pad or cap liner.

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is merely illustrative and that such changes may be made when desired as are within the scope of the appended claim.

What is claimed as new, is:—

The herein described horse collar including the following facing strips, to wit: a flexible rim piece, a facing or liner strip, a pair of crook pieces, a pair of wear strips, a pair of straights, a closing seam passing through the inner edges of each of the respective pieces, a shaping seam passing through each of the respective pieces at a point adjacent the outer edge thereof to provide around the collar a double reinforcing flange, and inner and outer neck band flaps secured to the upper edge of the straight pieces and provided with a series of openings.

In testimony whereof I affix my signature.

JOHN C. NICHOLS.
